W. H. ZACHMANN.
PORTABLE ELECTRIC LIGHT.
APPLICATION FILED JAN. 19, 1917.

1,241,071.

Patented Sept. 25, 1917.

Inventor

William H. Zachmann
By his Attorney
Henry T. Williams

UNITED STATES PATENT OFFICE.

WILLIAM H. ZACHMANN, OF WOODHAVEN, NEW YORK, ASSIGNOR TO NATIONAL CARBON COMPANY, OF LONG ISLAND CITY, NEW YORK, A CORPORATION OF NEW JERSEY.

PORTABLE ELECTRIC LIGHT.

1,241,071.

Specification of Letters Patent. Patented Sept. 25, 1917.

Application filed January 19, 1917. Serial No. 143,221.

To all whom it may concern:

Be it known that I, WILLIAM H. ZACHMANN, a citizen of the United States, residing at Woodhaven, Long Island, in the county of Queens and State of New York, have invented certain new and useful Improvements in Portable Electric Lights, of which the following is a specification, reference being had therein to the accompanying drawings, forming part thereof.

My invention relates to portable electric lights of the kind commonly called flashlights and relates more particularly to the flat or vest pocket type of these lights. Objects of my invention are inexpensiveness of manufacture, neatness and elegance of appearance, convenience of use, simplicity of construction, durability and other objects and advantages which will hereinafter appear.

My invention includes features of construction and combinations of parts as will appear from the following description.

I shall now describe the two vest pocket flashlights illustrated in the accompanying drawings as embodying my invention and shall thereafter point out my invention in claims.

Figure 1 is a side elevation of the complete flashlight with the casing open and with parts thereof omitted.

Fig. 2 is a central vertical section on a plane indicated by the line 2—2 of Fig. 1 as viewed from the right with the casing cover only slightly open and with the lamp and battery appearing in elevation.

Fig. 3 is a plan view as seen from above in Fig. 4.

Fig. 4 is a vertical section of the casing on a plane indicated by the line 4—4 of Fig. 1 as viewed from the left with the casing in closed condition and with the battery and other parts appearing in elevation.

Fig. 5 is an enlarged side elevation of the movable catch member appearing in Figs. 1, 2, 3 and 4.

Fig. 6 is an elevation similar to Fig. 1 of a slightly modified construction.

Fig. 7 is a central vertical section on a plane indicated by the line 7—7 of Fig. 6 as viewed from the right, and is a view similar to Fig. 2 of the construction illustrated in Fig. 6.

Fig. 8 is a view similar to Fig. 4 of the construction illustrated in Figs. 6 and 7,

and is a vertical section on a plane indicated by the line 8—8 of Fig. 6 as viewed from the left.

Fig. 9 is an enlarged elevation similar to Fig. 5 of the corresponding movable catch member appearing in Figs. 6, 7 and 8.

The vest pocket flashlight embodying my invention illustrated in the accompanying drawings has a rounded substantially rectangular elongated flat sheet metal casing which is divided in the plane of its largest dimensions, or in a plane parallel with its flat sides, into two similar halves 1 and 2 of which the rear part 1 may be called the battery-supporting and lamp-carrying half, and the front part 2 may be called the cover half. At their adjacent lower ends the two casing halves 1 and 2 are hinged together by means of a sheet metal hinge having leaves 3 and 4 and a pintle 5, the hinge leaf 3 being shown as secured by means of rivets 6 to the inside of the casing cover or front part 2, and the other hinge leaf 4 is shown as similarly secured by means of similar rivets 7 to the inside of the rear or battery-holding and lamp-carrying casing part 1.

The hinge leaf 4 of the rear casing part or casing half 1 is provided with an extension which is turned over outwardly in V-shape with the hinge leaf 4 so as to form at its spaced free edge a battery-supporting ledge or shelf 8, this battery-supporting ledge 8 being thus integral with or formed in one piece with the hinge-leaf 4, by the securing rivets 7 of which it is also firmly supported and held in place within the rear casing part 1 so that the hinge, having the leaves 3 and 4, and the battery support 8 at the bottom of the casing are combined.

The flat sheet metal casing comprising these two hinged halves 1 and 2 contains a usual flat form of dry battery 9 which, at its lower end, rests upon the battery support 8. The battery 9 is further held in proper position within the casing by means of an upper sheet metal support or abutment ledge 10. The battery-supporting abutment ledge 10 has a base 11 by means of which it is supported upon the rear casing part 1, this base 11 being suitably secured to the inside of the casing part, for example, by soldering it thereto.

At its end opposite to the hinge the rear or battery-holding casing part 1 is provided with or carries a metallic screw-threaded

lamp socket 12 which may be soldered in place in a semi-circular notch in the upper end of the rear casing part 1, the front casing part 2 at its upper end being provided with a similar semi-circular notch 12^a for removably fitting around the outer half of the lamp socket 12 in the closed condition of the casing, as appears in Fig. 4 of the drawings. The base 11 of the battery-restraining abutment ledge 10 is shown as extending upwardly at the back of the lamp socket 12 and is there turned outwardly and provided with a circular opening through which the lamp socket passes, so that this outwardly-turned part encircles or surrounds the lower or inner part of the lamp socket 12 at the inside of the casing and forms a brace 13 for the lamp socket, to which it may be soldered, this feature of construction being readily apparent from the drawings.

At the front or outwardly from the lamp socket 12 the lamp socket brace 13 is provided with a downwardly-turned lug or projection 14 which forms a stationary catch part which is coöperative with a movable catch part carried by the cover or front casing part 2, as will now be described. It is to be noted that the single member forming the upper battery support 10 and the lamp socket brace 13 and also the stationary catch part 14 is formed from a single piece of sheet metal.

The movable catch part carried by the upper end of the casing cover part 2 is shown as a slidable catch part mounted upon and guided by the outer casing part or cover 2. The cover or outer casing part 2 is provided near the upper end thereof with a slot 15 in which non-rotatively slides the flattened stem 16 of a stud having an outer rounded exposed head 17 providing for manual actuation of the slidable catch member or movable catch part. The movable catch stud is of reduced diameter inward from the flattened stem 16 so that the stem 16 forms a shoulder, as appears in Fig. 5, and the reduced inner part of this stud successively receives or carries a thin guide plate 18, a spacing washer 19 and an upwardly projecting and slightly inwardly inclined catch member 20, inward from which the reduced stem of the slidable catch stud is upset or rived as appears at 21 in Fig. 5. The movable catch member or catch plate 20 projects upwardly toward the upper end of the casing part 2 in position to be engaged at the inner side of the downwardly projecting stationary catch part or lug 14 in the closed condition of the casing, as appears in Fig. 1, or, on the other hand, to be released from the stationary catch part 14 to permit the outer casing half or cover part 2 to be opened, as appears in Figs. 1 and 2, it being apparent that move-

ment may be imparted to the movable catch part by means of the outwardly exposed manually actuatable rounded head 17, to which the thumb may be applied.

The battery 9 has the usual contact 70 springs or contact strips 22 and 23 which form the terminals of the battery at its opposite sides, the contact strip 22 being shown as of the usual short upright form and the other contact strip 23 being of 75 greater length and bent over at an angle so as to extend transversely across the upper end of the battery 9, as is usual. The transversely extending contact spring 23 is in position to press upon and form electrical 80 connection or contact with the central terminal 24 of a usual miniature incandescent lamp having a bulb 25 and a usual annular screw-threaded base 26, which, as shown, is screwed into and forms electrical connection with the lamp socket 12, which latter, as hereinbefore noted, is secured to and in electrical connection with the rear casing half or casing part 1.

A circuit controller is provided for electrically connecting the short upright battery terminal 22 with the rear or battery-holding casing part 1. In the construction illustrated in the drawings a reversely bent cam-shaped contact strip or contact spring 27 95 is secured at its lower part by means of rivets as shown to the inside of the margin of the casing part 1 and is adapted to be operated by means of a double-headed stud or button 28 which passes through a slot in 100 and is guided by the casing part 1.

In the slightly modified construction of flat or vest pocket flashlight illustrated in Figs. 6, 7, 8 and 9 of the accompanying drawings, the improvements of my invention 105 are shown as applied to a somewhat larger or three-cell vest pocket flashlight, the narrower construction hereinbefore described being a two-cell light. In this modified construction the battery-supporting extension 29 from the hinge leaf 30, which is similar to the hereinbefore described hinge leaf 4, is provided at the top with an in-turned horizontal table part 31 having a battery-supporting flat upper surface, as 110 clearly appears in the drawings.

Also in this modified construction it is to be noted that the stationary catch part 32 corresponding to the hereinbefore described stationary catch part 14 is of bifurcated or 120 forked construction, for receiving the larger neck part 33 of a simple slidable stud having also an inner head 34 which engages at the inner side of the bifurcated catch member 32 as appears in Fig. 8. This slidable 125 catch stud also has a smaller neck part 35 which is guided in a slot 36, similar to the hereinbefore described slot 15, in the front casing part. At the outside of the casing the movable catch stud, having the larger 130

neck 33, the inner head 34 and the smaller neck 35, is provided with a further reduced part 37 for receiving thereon a perforated button 38 through which the reduced stud 5 extension 37 is riveted flush with the outer surface thereof as shown in Fig. 9. The button 38 has an inner surface of quite some extent which is flat and is guided by the outer surface of the front casing part, and 10 the button 38 together with the stud carried thereby forms a slidable catch part or catch member which is manually actuatable by means of the exposed button 38, which may be moved either up or down by the thumb. 15 In other respects than above noted the modified construction illustrated in Figs. 6 to 9 inclusive is substantially the same as that hereinbefore described in reference to Figs. 1 to 5 inclusive.

20 It is obvious that various modifications may be made in the constructions shown in the drawings and above particularly described within the principle and scope of my invention.

25 I claim:

1. An oblong flat casing for a portable electric light divided into front and rear halves along its largest dimensions, a hinge uniting the two halves at one end, a lamp 30 socket carried by the rear half at the end thereof opposite to the hinge, a battery support in the rear casing half adjacent to the lamp socket, and a releasable catch for the hinged halves having a stationary catch part 35 carried by the said battery support adjacent to the lamp socket and having a movable catch part carried by the front casing half.

2. An oblong flat casing for a portable 40 electric light divided into front and rear halves in the plane of its largest dimensions, a hinge uniting the two halves at one end, a lamp socket carried by the rear half at the end thereof opposite to the hinge, a 45 battery support in the rear casing half formed as a part of the hinge, a second battery support in the rear casing half adjacent to the lamp socket, and a releasable catch for the hinged halves having a stationary catch part carried by the second battery support 50 adjacent to the lamp socket and having a movable catch part carried by the front casing half.

3. An oblong flat casing for a portable 55 electric light divided into two halves in the plane of its largest dimensions, and a hinge uniting the two halves at one end and having a leaf of the hinge provided with a turned-out extension forming a battery sup-

60 port.

4. An oblong flat casing for a portable electric light divided into front and rear

halves in the plane of its largest dimensions, a hinge uniting the two halves at one end and having a leaf thereof provided with a 65 turned-over extension forming a battery support in the rear half, a lamp socket carried by the rear casing half at the end thereof opposite the hinge, a second battery support in the rear casing half adjacent to the lamp 70 socket and having a projection forming a stationary catch part adjacent to the lamp socket, and a movable catch part carried by the front casing half and co-operative with the stationary catch part. 75

5. An oblong flat casing for a portable electric light provided into front and rear halves in a plane parallel with the flat sides, a hinge uniting the two halves at one end and having one of its leaves secured at the 80 inside of one of the halves and having its other leaf secured at the inside of the other half, a battery-supporting ledge for the bottom of the battery in the rear casing half formed by a turned-over part of the corresponding hinge leaf, a lamp socket carried by the rear casing half at the end thereof opposite the hinge, a member encircling the lamp socket at the inside of the rear casing half and forming a second or upper battery 85 support and also forming a brace for the lamp socket and also forming a stationary catch part adjacent to the lamp socket, and a slid- 90 able catch part guided by the front casing half and co-operative with the stationary catch part at the inside of the casing and exposed for manual actuation at the outside of the casing.

6. A casing for a portable electric light, comprising front and rear casing halves 100 hinged together, a lamp socket carried by the rear casing half, and a member carried by the rear casing half, and forming a battery support and also forming a brace for the lamp socket and also forming a catch 105 part.

7. A casing for a portable electric light, comprising two casing halves, and a hinge 110 uniting the two casing halves and provided with a battery support.

8. A casing for a portable electric light, comprising two casing halves hinged together, and a combined battery support and catch member carried by one of the casing 115 halves.

9. A casing for a portable electric light, comprising two casing parts hinged together, and a combined brace for the lamp socket and catch member carried by one of the casing parts. 120

In testimony whereof I have affixed my signature.

WILLIAM H. ZACHMANN.
